UNITED STATES PATENT OFFICE.

HENRY REILY, OF RIXFORD, PENNSYLVANIA.

STAY FOR CORSETS.

SPECIFICATION forming part of Letters Patent No. 296,063, dated April 1, 1884.

Application filed June 11, 1883. (Model.)

To all whom it may concern:

Be it known that I, HENRY REILY, of Rixford, in the county of McKean and State of Pennsylvania, have invented certain new and useful Improvements in Stays for Corsets and Dresses; and I do hereby declare the following to be a full, clear, and exact description of the invention, such as will enable others skilled in the art to which it pertains to make and use it, reference being had to the accompanying drawing, which forms part of this specification.

My invention relates to an improvement in stays for dresses and corsets; and it consists in a double-coiled flattened spring, in combination with a plate to which the spring is attached, as will be more fully described hereinafter.

The object of my invention is to produce a flexible stay for dresses and corsets which will conform readily and easily to every movement of the body, and which is cheaply produced and very durable.

The accompanying drawing represents my invention.

A represents a double spiral or coiled spring, which is flattened, as shown, and which is made of one continuous wire. The flattening of the spring may be done by the machine while the spring is being formed, or an ordinary spiral spring may be taken and then flattened, as may be preferred. These flattened springs will be applied to dresses and corsets, either singly or in pairs, as may be preferred. Where used as the main stay of a corset, they will be used in pairs, as here shown, and will be attached to plate C, which has small points

D struck up therefrom, and has the corners or ends of the points bent over, so as to clasp the springs and bind the two parts securely together. By flattening the springs a much wider and stronger stay is produced without the thickness which would otherwise be necessary, and hence better and stronger stays can be produced. Were spiral springs of the size here shown used, their thickness would cause ridges or bulges upon both the corset and dress, and thus present an unsightly appearance. Where very small fine spiral springs are used they do not give the required support that is necessary, either to the dress or to the corset, and hence are objectionable on this account.

I am aware that a flattened coiled-wire spring which is rolled down upon a suitable foundation is not new, and this I disclaim. My invention differs from this in making a double spring which is attached to the plate by means of suitable points or projections, as shown.

Having thus described my invention, I claim—

A double-coiled flattened spring, A, in combination with the plate C, the plate C being provided with points D, which are bent down over the spring to secure the two parts together, substantially as shown and described.

In testimony whereof I affix my signature in presence of two witnesses.

HENRY REILY.
